CLAIM

I claim the ornamental design for the safety razor actuator button, as shown and described.

DESCRIPTION

FIG. 1 is an upper perspective view of a safety razor actuator button.

FIG. 2 is a top view thereof.

FIG. 3 is a left side view of FIG. 2.

FIG. 4 is a right side view of FIG. 2.

FIG. 5 is a side view thereof; and,

FIG. 6 is an opposed side view thereof.

1 Claim, 2 Drawing SheetsFIG. 1

FIG. 2

FIG. 3

FIG. 4

FIG. 5

FIG. 6
